(57) **CLAIM**

The ornamental design for a projector equipped with a lamp, as shown and described.

DESCRIPTION

FIG. 1 is a perspective view of a projector equipped with a lamp showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-sectional view taken along line 8-8 in FIG. 2 thereof;

FIG. 9 is an enlarged view of the circled portion so indicated in FIG. 1 thereof;

FIG. 10 is an enlarged view of the circled portion so indicated in FIG. 6 thereof;

FIG. 11 is an enlarged view of the circled portion so indicated in FIG. 8 thereof;

FIG. 12 is a perspective view thereof in a state that the projector equipped with a lamp is rotated by a certain angle;

FIG. 13 is a perspective view thereof in a state that the projector equipped with a lamp is rotated by 180 degrees; and,

FIG. 14 is a perspective view thereof in a state that the projector equipped with a lamp is rotated by 270 degrees. The dot-dashed broken lines represent a boundary of the claimed design and form no part of the claimed design. The dashed broken line showing of portions of the projector equipped with a lamp is for the purpose of illustrating unclaimed portions of the projector equipped with a lamp and forms no part of the claimed design.
